[57] **CLAIM**

The ornamental design for a platform type shoe sole, as shown and described.

DESCRIPTION

FIG. 1 is a left side elevational view of a platform type shoe sole showing my new design; the right side being a mirror image thereto;

FIG. 2 is a front elevational view thereof;

FIG. 3 is a rear elevational view thereof;

FIG. 4 is a bottom plan view thereof, the top being flat, plain, and unornamented.
